UNITED STATES PATENT OFFICE.

WOLFGANG E. SCHWARZMANN, OF LONG MEADOW, AND CHARLES M. WILD, OF SPRINGFIELD, MASSACHUSETTS, ASSIGNORS TO BOSCH MAGNETO COMPANY, OF NEW YORK, N. Y., A CORPORATION OF NEW YORK.

APPARATUS FOR WINDING COIL-CONDENSERS.

1,260,819.

Specification of Letters Patent. Patented Mar. 26, 1918.

Application filed May 16, 1916. Serial No. 97,940.

To all whom it may concern:

Be it known that we, WOLFGANG E. SCHWARZMANN and CHARLES M. WILD, residing at and whose post-office addresses 5 are 51 Belleclaire avenue, Long Meadow, and 14 Springfield street, respectively, in the city of Springfield, county of Hampden, State of Massachusetts, have invented certain new and useful Improvements in Apparatus for Winding Coil-Condensers; and we do hereby declare the following to be a full, clear, and exact description of the invention, such as will enable others skilled 10 in the art to which it appertains to make and use the same.

It is essential that electric static condensers of the coil type should, for some purposes, be wound tightly without localized strains to form a compact and almost solid 20 body capable of withstanding considerable mechanical stress and having a maximum electrostatic capacity within the space occupied. For instance, the condensers associated with the armatures of magneto-electric 25 machines for ignition purposes, are subjected to considerable centrifugal action, and the space available is quite limited considering the capacity required to satisfactorily suppress the sparks at the co-operative electrical 30 trodes of the mechanical interrupter. It has been suggested that the coil condensers be wound loosely and then subjected to pressure to increase their solidity and capacity by pressing the adjacent bands into intimate 35 contact, and preferably after the loosely wound condensers have been heated moderately for a number of hours so as to soften the paraffin or other material impregnating the paper. This procedure subjects the 40 curved ends of the bands to considerable strain in pressing the coil to the flat, oval, or other form desired, and often the foil bands are partly or entirely ruptured, with the result that some of the capacity of the condenser is lost, especially when the terminals 45 are connected to the ends of the foil bands.

The object of this invention is to provide apparatus for winding coil condensers so tightly that a practically solid body having 50 no internal mechanical strains but having the maximum of electrostatic capacity within the space occupied, is produced directly, that is, without being subsequently subjected to heat, pressure or other treatment. We at-

tain this result in winding round, oval or 55 other shaped condensers by subjecting the bands of foil to a considerable tension in winding them onto the core to form the condenser, and preferably also in subjecting the bands of dielectric to tension. To do 60 this satisfactorily, the reels of foil and dielectric are subjected to such frictional resistance to rotation that the separate bands are tensioned to the desired degree in feeding them onto the core of the condenser 65 being wound, and the bands are maintained in lateral position throughout so that there is no tendency for the bands to tear at the edges under that tension. If desired the condenser may also be subjected to the pressure 70 of a spring-pressed roller as it is wound onto the core, to thereby press the bands more intimately together and to give the finished coil an added degree of solidity.

In winding coil condensers of the side 75 contact type, wherein the two foil bands project laterally on opposite sides to provide continuous side terminals for the condensers, it is more important than would otherwise be the case that the bands be maintained accurately in lateral position at all times, particularly where the side extensions of the bands are quite limited, as in comparatively narrow coils suitable for magneto-electric 80 machines. The apparatus herein disclosed 85 provides for this contingency by providing laterally adjustable guides for the separate coils of foil and dielectric. These supports not only maintain the bands in lateral position throughout, but also provide means for 90 adjusting the amount of lateral extension of either or both of the foil bands.

The apparatus has other features important in the production of satisfactory coil condensers of this kind. For instance, it is 95 essential that the condenser core should be suitably supported in winding position and should be capable of being readily installed and removed from the apparatus. Furthermore, the bands should be gripped and held 100 in unalterable relation when a condenser is being removed and the next core installed, so that in starting to wind the next condenser thereon, the bands of foil will have the proper lateral extension, and the tension 105 to which the bands are subjected will not cause rupture during the start of the operation. It is also desirable to provide means

for indicating the presence of a short-circuit between the bands of foil on the condenser due to an imperfection in the separating dielectric, and we provide for this in such 5 a way that an indication is given immediately that the short-circuit occurs. These and other features are nicely provided for in the apparatus, as will appear hereinafter.

In the accompanying drawings illustrating 10 the preferred form of apparatus for winding oval condensers of the side terminal type, as an example,

Figure 1 is a plan view of the apparatus with the bands broken away for a part of 15 their length; Fig. 2 is a side elevation thereof; Fig. 3 is an enlarged section on line 3—3 of Fig. 1; Fig. 4 is an enlarged section on line 4—4 of Fig. 1; Fig. 5 is an enlarged plan view, partly in section, showing the 20 method of attaching the condenser core in place on the winding apparatus and the arrangement of the bands wound thereon; Fig. 6 is an enlarged side view of the gripping device for the bands; Fig. 7 is an enlarged 25 front view thereof; Fig. 8 is similar to Fig. 6 except that the movable jaw is turned to gripping position; and Fig. 9 is an enlarged side elevation of the condenser core.

The rigid base plate 1 supports the standards 2, 3, 4 and 5 for the rotatable reels 6, 30 7, 8 and 9, which contain the bands of foil, varnished paper, foil and varnished paper, in the order named. The bands pass from the bottom of the respective reels underneath 35 the rollers 10 and stationary cam guides 11, and then converge toward the stationary cam guides 12 over which they pass to and around the rollers 13 so as to loop back to the top of the condenser core 40 14. The fly wheel 15 carries the turning handle 16, or may be motor driven, and supports at its center the condenser core, which is screwed into place so as to be readily fastened to the fly wheel and then removed 45 therefrom when the condenser is completely wound on it. As a result of this construction, it will be observed that the cams 11 and 12, the rollers 13, and the support for the condenser being wound are, like the standards 50 with their guiding rollers, mounted rigidly on the base plate 1. The roller 17 presses on the top of the condenser as it is being wound, substantially at the place the bands first come into contact with each other, 55 and is carried by an arm 18 pulled downwardly by the spring 19.

Each of the standards for the spools is provided with a friction brake (Fig. 3) comprising a brake shoe 20 spring-pressed into 60 contact with the flanged hub 21 of the axle 22. The tension in the bands depends upon the resistance to movement of the bands in winding them onto the core. This resistance is made up in part by the friction of the 65 bands in sliding past the guide cams 11 and

12 and in turning the rollers 10 and 13. To this is added the frictional resistance of the brake shoes 20, whereby each band is tensioned more uniformly throughout its length between the condenser core and the reel from 70 which the band is fed. In order that the tension on the bands may be increased without danger of rupture, the bands are maintained in lateral position throughout, as will appear hereinafter, so that there is no tendency 75 for them to tear at their edges. By maintaining the bands of foil under tension, and also by maintaining the bands of dielectric under tension too, the condenser attains directly a high degree of solidity, 80 and by providing the pressure roller 17, the degree of solidity is increased, whereas the varnish on the paper is smoothed out and made uniform throughout. By maintaining the bands under tension as aforesaid, 85 and also by providing the pressure roller 17, the adjacent bands are brought into intimate contact throughout, producing also a condenser of the maximum capacity within the space occupied. A condenser like that 90 illustrated and having about one hundred turas has a capacity of .15 microfarad.

It has been found that if rollers like 10 or 13 are used instead of the guide cams 11 and 12, in order to decrease the resistance 95 at those places to the movement of the bands, the varnish on the paper may sometimes adhere to the rollers with such tenacity as to cause rupture of the band, especially upon starting the machine after it has been 100 stopped for some time, owing to the increase that would occur in the area of contact between the varnished paper and the rollers. By using rollers and cams of the cross sectional shape illustrated, this trouble 105 is entirely eliminated even though the varnished paper is unusually sticky.

The bands are maintained in lateral position throughout by positioning the reels, together with the cams and rollers over which the bands pass, in alinement with each other, 110 as may be seen from Fig. 1. This is particularly important where the condenser to be wound is of the type in which the bands of foil project on the opposite sides to form 115 continuous side contacts, inasmuch as the amount of lateral extension is rather limited, especially in case of narrow condensers suitable for use in magnetos. The proper alinement is obtained and preserved 120 by laterally adjusting the reels by means of the threaded bolts 23, and laterally adjusting the guide cams 11 and 12 by similar means. The rollers 10 and 13 are wider than the bands and provide for slight lateral adjustment of the bands.

If desired, a pin 24 may be provided on the fly wheel pedestal 25 to contact with the condenser and thereby furnish an indication 125 to the operator when a sufficient number of 130

turns has been wound on the condenser. The bands are then torn off at the condenser and the condenser is removed from winding position by unscrewing the core 14 from the fly 5 wheel 15. If the free ends of the bands were not held at this time in unalterable relation, the condenser next wound by the apparatus might be defective in that the bands would not have the proper alinement. In order to 10 overcome this difficulty, a gripping device tightly gripping the bands before they are torn apart to remove the condenser is provided. The gripping device comprises a support 26 having a horizontal outstanding 15 jaw 27 under which the bands pass in being wound on the condenser. The coöperative jaw 28 is normally held against the under side of the jaw 27 by a spring 29, and when in that position, it is prevented from turning 20 by the pin 30. In winding the condenser, the bands pass underneath the jaw 27 and just to one side of the jaw 28, but before the bands are torn off to remove the condenser, the jaw 28 is pushed down until it is beyond 25 registry with the pin 30, and is then given a quarter of a turn to the position shown in Fig. 8. The jaw 28 is then released and is forced by the spring 29 toward the under side of the jaw 27 so as to tightly grip the 30 bands and thereby maintain them in unalterable position. Upon starting to wind the next condenser, the jaw 28 is turned back to its normal position, shown in Figs. 6 and 7, and the bands are pulled over to the core 35 and fixed to an insulating fiber sleeve thereon by means of paste. The pressure roller 17, which, while a finished condenser is being removed, is raised to the inoperative position shown in broken lines in Fig. 2, and 40 locked in that position by the hook 31, is then released and lowered into contact with the core on which the next condenser is to be wound.

Inasmuch as commercial varnished paper 45 is apt to contain pin holes or other defects which may result in a short-circuit between the bands of foil, means are provided to immediately indicate the presence of a short circuit during the winding operation. For 50 this purpose an incandescent lamp 32 is connected to a source of current supply and to the two bands of foil 6 and 8, which are normally insulated from each other throughout their length. The pedestal 2 is insulated 55 from the base plate 1, and the one cam 11 and the other cam 12, together with the roller 13 over which the band of foil passes, are likewise insulated. The pedestal 2 is connected to one stud of a switch 33 and one 60 terminal of the incandescent lamp 32 is connected to the other stud of the switch. The terminals of the source of current supply (not shown) are connected to the other terminal of the incandescent lamp and to the 65 base plate 1. When the switch 33 is closed,

the incandescent lamp 32 lights up immediately that a short circuit occurs in the paper between the bands of foil, the current then flowing through the base plate 1 and the band 8 of foil, and thence through the short 70 circuit in the condenser to the insulated band 6 of foil, which is connected to the lamp 32 through the switch 33, the lamp being extinguished at all other times. The two bands of foil 6 and 8 are kept out of 75 contact with each other at the beginning and end of the condenser, by tearing off the ends of one of the bands of foil a little way from the ends of the other band of foil, and in the side contact type of condenser, the terminals 80 of the condenser are formed at the two sides thereof by the laterally projecting bands of foil 6 and 8.

The foregoing apparatus is effective to produce a condenser of a high degree of 85 solidity, and as a result the condenser is capable of withstanding considerable stress and has a large capacity in proportion to the space occupied. Although a coil condenser of oval shape is shown, it is apparent 90 that the condensers may be wound directly in a round or flat form, if desired, without introducing mechanical strains at any place, as is the case at the curved ends of condensers which are pressed into shape after 95 being wound.

Having thus described our invention, what we claim is:

1. In apparatus for winding coil condensers, a rotatable condenser support, a 100 plurality of supports on which reels of foil and dielectric are mounted for rotation, and guides maintaining the bands separated from each other throughout their entire 105 unwound length.

2. In apparatus for winding coil condensers, a rotatable condenser support, a 110 plurality of supports on which reels of foil and dielectric are mounted for rotation, guides maintaining the bands separated from each other throughout their entire unwound length, and a pressure roller engaging the bands at substantially the place they first come into contact with each other 115 at the condenser support.

3. In apparatus for winding coil condensers, a rotatable condenser support, a 120 plurality of supports on which reels of foil and dielectric are mounted for rotation, guides maintaining the bands separated from each other throughout their entire unwound length, and braking means resisting the rotation of the reels in unwinding the bands therefrom.

4. In apparatus for winding coil condensers, a rotatable condenser support, a 125 plurality of supports on which the reels of foil and dielectric are mounted for rotation, and a plurality of guides consisting of rollers and cams for guiding the bands of di- 130

electric from the reels to the core, the cams and rollers being constructed and arranged to prevent the bands of dielectric from adhering with sufficient tenacity to rupture them.

5. In apparatus for winding coil condensers, a rotatable condenser support, a plurality of supports on which the reels of foil and dielectric are mounted for rotation, 10 and a plurality of guides consisting of rollers and cams for guiding the bands of dielectric to guide each band separately from its reel to the core, the cams and rollers being constructed and arranged to prevent the 15 bands of dielectric from adhering with sufficient tenacity to rupture them.

6. In apparatus for winding coil condensers, a rotatable condenser support, a plurality of supports on which the reels of 20 foil and dielectric are mounted for rotation, and a plurality of guides for the bands, some of said guides being located beyond the condenser support so that the bands are looped back in being wound onto the support.

7. In apparatus for winding coil condensers, a rotatable condenser support, a plurality of supports on which the reels of foil and dielectric are mounted for rotation, 30 guide rollers located beyond the condenser support so that the bands are looped back in winding them onto the support, guide rollers carried by the supports for the reels, and guide cams between the guide rollers 35 on the reel supports and the guide rollers beyond the condenser support.

8. In apparatus for winding coil condensers, a condenser support, a plurality of supports on which the reels of foil and dielectric are mounted, guides located beyond 40 the condenser support so that the bands are looped back in winding them onto the condenser support, guides carried by the supports for the reels, and guides between the 45 guides on the reel supports and the guides beyond the condenser support.

9. In apparatus for winding coil condensers, a base plate, a plurality of reel

standards spaced along the base plate, a condenser support mounted on the base 50 plate, and guides mounted on the base plate on both sides of the condenser support for guiding the bands in a looped course as they are wound onto the condenser support.

10. In apparatus for winding coil condensers, a core on which the condenser is wound, a rotatable support on which the core is mounted, means for rotating said support, a plurality of supports on which the reels of foil and dielectric are mounted, and a gripping device in proximity to the core and constructed and arranged to permit the uninterrupted passage of the bands in winding them onto the core and also to hold the ends of the bands in unalterable relation to each other upon removing the finished condenser from the support.

11. In apparatus for winding coil condensers, a rotatable support for the core on which the condenser is wound, means for 70 rotating said support, a plurality of supports on which the reels of foil and dielectric are mounted, and a gripping device comprising a fixed jaw and a co-operative movable jaw having one position in which 75 the bands are permitted to have uninterrupted passage in being wound onto the core, and having another position in which the bands are held between the jaws in unalterable position relatively to each other upon 80 removing the finished condenser from the support.

12. The combination with apparatus for winding coil condensers in which the bands of foil are separated by bands of dielectric, 85 of short-circuit indicating mechanism comprising an indicator and an electric circuit connected to the bands of foil, those parts of the apparatus which support the bands of foil in winding them onto the condenser 90 core being insulated from each other.

In testimony whereof we affix our signatures.

WOLFGANG E. SCHWARZMANN.
CHARLES M. WILD.
